DEVICE FOR SWITCHING-IN AND DIS-
CONNECTING SIGNAL APPARATUSOtto Tschumi, Soleure, Switzerland, assignor to
Autophon Aktiengesellschaft, Soleure, Switzerland, a joint-stock company of SwitzerlandApplication May 12, 1944, Serial No. 535,296
In Switzerland December 4, 1942

5 Claims. (Cl. 179—81)

This invention relates to devices for switching-in and disconnecting signal apparatus. In devices of this kind known up to date, switching-in and disconnecting a signal apparatus require a short-period operation of a switch specially provided for this purpose.

The device according to the invention remedies this inconvenience. It is of the kind comprising a dial for calling the subscribers and is characterised in that the switching-in and disconnecting is caused by operating the dial's sparking and impulse contacts necessary for calling the subscribers. Owing to this feature no additional switching elements are necessary in that both the sparking contact and the impulse contact, in spite of their additional use, are in no way prevented from fulfilling their original purpose.

The accompanying drawing illustrates, by way of example, one embodiment of the object of invention.

Fig. 1 is a diagram of this example and

Fig. 2 shows a calling dial with special characters.

The signal apparatus N shown in Fig. 1 may be an acoustic means of communication with loud-speaker and microphone, or a teletype transmitting and receiving apparatus, etc. This apparatus N is connected by means of the terminals 1 and 2 with the installation over which the connections are to be established. Between the terminal 2 and the signal apparatus N the calling dial NS with the impulse contact *i* and the sparking contact *k* is switched-in. The sparking contact *k* is in single-pole connection with the impulse contact *i*. In Fig. 1 this sparking contact *k* bridges-over the signal apparatus N; this fact, however, is not an essential feature of the invention, for it might, with the same effect, just as well be connected-in at the place *a*. Between the terminal 1 and the signal apparatus N lies the relay R with the contacts *r*₁ and *r*₂, the latter controlling the optical signal SZ. Contact *r*₁ is bridged-over by the condenser C.

If the apparatus is to be disconnected by the subscriber himself, the calling dial NS illustrated in Fig. 2 is rotated with the finger in the hole of the first figure to be dialled. Thereby, the sparking contact *k* is closed, whereby a current circuit is formed going from a power source connected to the terminal 1 over the relay R, sparking contact *k*, impulse contact *i*, to the terminal 2 and from here back to the power source. Relay R comes into action and closes the contacts *r*₁ and *r*₂ with the effect that, on the one side, a circuit is established over terminal 1—relay R—signal

apparatus N—contact *r*₁—impulse contact *i*—terminal 2, whereby the signal apparatus N is connected-in while, on the other side, this operating condition is indicated by a flashing-up of the optical signal SZ. The calling dial can now be let go and the device remains ready for selection owing to the position of contact *r*₁.

If the apparatus is remote-controlled, an alternating current impulse reaches the relay R over 10 the condenser C and the contact *r*₁, thereby rendering possible the same operations as if the subscriber himself would have controlled the apparatus.

Should it be expected that between the moment 15 of the switching-on and the selection readiness there would be an undesirably great time interval, it is suitable to effect the switching-on by dialling the character E specially provided for this purpose, instead of dialling the first figure 20 to be selected. By dialling the character E the sparking contact *k* is short-circuited, however, without impulses being given during the movement of the dial. Finally, the disconnecting process is begun by dialling the special character A. 25 Dialling this character causes the opening of the impulse contact *i*, which opening continues even during the return movement of the dial until the sparking contact *k* is open. Thereby the current in the relay R is interrupted, contact *r*₁ drops back and the signal apparatus N is disconnected.

Furthermore, the arrangement according to 30 which the switching-in of the signal apparatus is caused merely by dialling the first figure necessary for the connection desired has the very important advantage that the holding time of the station is considerably reduced in that the subscriber must first realise which figures are to be dialled before he can begin the connecting process.

What I claim is:

1. In an installation, a signal apparatus, and a device for switching-in and disconnecting said signal apparatus, comprising a dial including a 45 sparking contact and an impulse contact necessary for calling the subscribers, said signal apparatus being arranged so that its switching-in and its disconnecting is caused by operating said sparking contact and said impulse contact.
2. In an installation according to claim 1, said signal apparatus being arranged so that its disconnecting is caused by dialling the first figure of the subscriber's number to be selected.
3. In an installation, a signal apparatus, a device for switching-in and disconnecting said sig-

nal apparatus, comprising a dial including a sparking contact and an impulse contact necessary for calling the subscribers, said signal apparatus being arranged so that its switching-in and its disconnecting is caused by operating said sparking contact and said impulse contact, a direct current circuit able to establish the readiness for selection, and means destined to indicate to the selecting subscriber the closing of said direct current circuit.

4. In an installation, a signal apparatus, a device for switching-in and disconnecting said signal apparatus, comprising a dial including a sparking contact and an impulse contact neces-

sary for calling the subscribers, said signal apparatus being arranged so that its switching-in and its disconnecting is caused by operating said sparking contact and said impulse contact, a direct current circuit able to establish the readiness for selection, and an optical signal destined to indicate to the selecting subscriber the closing of said direct current circuit.

5. In an installation according to claim 1, said dial having special characters destined to cause the switching-in and the disconnecting of said signal apparatus.

OTTO TSCHUMI.
